ESCAPE SCUTTLE

Joseph P. Castellano, Brooklyn, N. Y.

Application June 30, 1945, Serial No. 602,642

8 Claims. (Cl. 293—6)

(Granted under the act of March 3, 1883, as amended April 30, 1928; 370, O. G. 757)

1

This invention relates to an escape scuttle and more particularly to a cover therefore that can be quickly opened to permit the passage of personnel and then rapidly closed and sealed.

Escape scuttles are commonly placed in decks and bulkheads of boats and ships to provide access to a deck or from one compartment to another. They are generally kept closed but on occasion, such as an emergency, it is essential that they can be opened and closed rapidly and easily. With the present invention, rotation of a single wheel will actuate the locking mechanism of the cover permitting it to be unlocked and opened or closed and locked.

An object of this invention is to provide a cover for an escape scuttle that can be quickly unlocked and opened or closed and locked.

Another object is to provide such a cover having locking mechanism that is positive acting and can be actuated with a minimum of effort.

Still another object is to provide locking mechanism for an escape scuttle cover which is of relatively simple construction and will not jam or get out of order.

Further objects and advantages of this invention, as well as its construction, arrangement and operation, will be apparent from the following description and claims in connection with the accompanying drawings in which

Figure 1 is a plan view of the under side or inside of an escape scuttle embodying the present invention with the inner handwheel removed,

Figure 2 is a cross-sectional view partly in elevation taken along the lines 2—2 of Figure 1 with the addition of portions of the inner handwheel spokes,

Figure 3 is an enlarged view of one of the locking mechanism employed, with the retracted position of the cam shown in dotted lines, and

Figure 4 is a side expanded view of a cam for use in the present invention and its cooperating roller bearing.

The drawings show an escape scuttle having a cover 11 pivotally connected to a deck or bulkhead 12 by a hinge 13 mounted on a support 14 extending from the deck. The cover 11 fits over the coaming 15 of an escape opening in the deck. The coaming 15 shown herein is a metal band which is preferably welded in the opening and projects outwardly toward the cover 11. It may also extend a short distance beyond the opposite side of the deck forming a flange 16. While the cover and opening are preferably round as shown herein they may be square or of other regular shape.

2

The cover 11 is provided with a peripheral flange 17 of greater diameter than the diameter of the coaming. A stiffening ring 18 is positioned on the inside of the cover 11 between the outer flange 17 and an inner stiffening flange 19. Overlying the stiffening ring 18 is an annular gasket 20 preferably made of resilient material such as rubber. Gasket keepers 21 hold the gasket 20 in place. With the cover 11 in closed position the gasket 20 abuts the outer rim of the coaming 15 and seals the opening.

The cover 11 is provided with a central opening in which a bushing 22 is positioned. A shaft 23 extends through the bushing 22 projecting a distance on each side of the cover. The space between the bushing 22 and the shaft 23 is filled with packing 24 secured in place by a gland packing washer 25 and a gland screw 26.

A preferably circular cam plate 28 having reinforcing ribs 29 is secured to the inner portion of shaft 23 by a spline 30. To permit easy rotation of the cam plate with respect to cover 11 a ball bearing is positioned between the two, the upper race 31 being secured to the cover 11 and the lower race 32 being carried by the cam plate 28.

Also splined to the shaft 23 are handwheels 33 and 34, the former being positioned adjacent the outer end of shaft 23 and the latter adjacent the inner end of the shaft. Nuts 35 screwed on the ends of shaft 23 hold the handwheels on the shaft.

In the preferred construction three curved cams 36 are welded to the inner or underside of the cam plate 28 adjacent the periphery thereof as shown particularly in Figure 1. As the cams 36 are identical it will suffice to describe one of them. Throughout one end portion, cam 36 has a uniform curvature so as to parallel the periphery of the cam plate 28. The opposite end portion of the cam is more sharply bent so that it gradually approaches closer to the center of the cam plate 28. The cam 36 increases in depth from one end to the other. It is of uniform depth throughout the portion of sharpest curvature and then gradually increases in depth to a point near its outer end, where it decreases slightly to provide a locked position and prevent back up as illustrated in Figure 4. Thus, the end of the cam 36 adjacent the periphery of the cam plate 28 projects farther from the cam plate than the inner end of the cam.

Three equally spaced dog carriers 37 are secured by welding or other suitable means to the inner side of the cover 11 radially outwardly of the cam plate 28. Each dog carrier 37 is substantially U-shaped in cross section with a base 55 and two sides forming a central longitudinal slot,

and is positioned so the slot extends substantially radially of the cover 11.

In the preferred arrangement one side of the slot lies along a radial line of the cover. An adjusting screw 38 extends through the base of the dog carrier 37 into the slot preferably substantially midway between the ends thereof, and operates as a fulcrum for the dog 43. It is provided with a locking nut 39. A compression spring 40 and a compression-spring bushing 41 are positioned in an upwardly extending bore in the inner end of the dog-carrier base with the bushing 41 extending above the base.

A dog 43 is slidably positioned in the longitudinal slot of each dog carrier 37 so that it may be moved inwardly toward the center of the cam plate or outwardly toward the periphery of cover 11. The outer end of dog 43 is cut away to provide a lip portion 44 which, when the dog is moved outwardly, engages the flange 16 of the coaming 15. The opposite or inner end of the dog 43 is provided with a stud shaft 45 adjacent the bottom of the dog about which a roller bearing is mounted. The inner ball race 46 is fixed to the stud shaft 45 and the outer race 47 rotates about the balls 48. A bearing keeper 49 maintains the bearing in place.

The upper, inner end of the dog 43, together with the upper end of the bearing keeper 49 and the rotating surface of the bearing form a slot 50 in which the cam 36 rides. In order to reduce friction, the portions of the dog 43 and bearing keeper 49 forming the sides of the slot 50 are rounded as shown in Figure 1.

A dog keeper 52 is pivotally connected to a pin 53 extending between the sides of the dog carrier 37 above the dog 43. Mounted on the dog keeper 52 is a compression-spring pilot 52a for maintaining a compression spring 54 in position between the dog keeper 52 and the inner face of the cover 11. The compression spring 54 urges the dog 43 against the exposed end of the adjusting screw 38 in the bottom of the dog carrier 37.

To operate the locking mechanism it is necessary only to rotate one of the handwheels 33 or 34 part of a complete rotation. Starting with the dogs 43 in the inner or unlocked position shown in dotted lines on Figure 3, rotation of the cam plate 28 first moves the dogs 43 outwardly, their full distance. During this part of the operation the inner ends of the dogs are urged upwardly by spring 40 which results in the dog lip 44 being slightly spaced from or only lightly touching the coaming flange 16. Further rotation of the cam plate forces the inner ends of the dogs 43 towards the base of the dog carrier 37 and rocks the dog on the fulcrum provided by the adjusting screw 38 to bring the dog lip 44 tightly against the coaming flange 16, thus sealing the hatch. Rotating the cam plate 28 in the opposite direction reverses the action hereinabove described and permits the cover 11 to be opened.

While reference has been made to the use of the escape scuttle in boats and ships, it may also be used in walls, ceilings or similar structures.

It is to be understood that various modifications and changes can be made in this invention without departing from the spirit and scope thereof as set forth in the appended claims.

The invention described herein may be manufactured and used by or for the Government of the United States of America for governmental

purposes without the payment of any royalties thereon or therefor.

What is claimed is:

1. A closure mechanism adapted for use in an escape scuttle comprising a cover shaped to fit an escape opening, a cam plate centrally and rotatably mounted on one side of said cover, a curved cam secured to said plate adjacent the periphery thereof having one end closer to the point of rotation of said plate and projecting a lesser distance from said plate than the other end, a dog carrier fixedly mounted on said cover outwardly of said cam having a guide slot therein extending substantially radially of said cover, a dog of less height than the height of said slot slidably positioned in said slot, said dog having a groove adjacent the inner end for engaging said cam, a member projecting from the bottom of said dog carrier into said slot to permit longitudinal rocking movement of said dog, resilient means tending to maintain said dog adjacent said projecting member, resilient means for urging the inner end of said dog toward said cam, and means for rotating said cam plate whereby said dog may be moved longitudinally and rocked in said slot.

2. A closure mechanism adapted for use in an escape scuttle comprising a cover shaped to fit an escape opening, a substantially round cam plate centrally and rotatably mounted on the inner side of said cover, a curved cam secured to the exposed side of said plate adjacent the periphery thereof having one end closer to the center of said plate and projecting a lesser distance from said plate than the other end, a dog carrier fixedly mounted on the inner side of said cover outwardly of said cam having a guide slot therein extending substantially radially of said cover, a dog slidably positioned in said slot and having a groove adjacent the inner end for engaging said cam, resilient means tending to maintain said dog adjacent the bottom of said slot, an adjustable member projecting from the bottom of said dog carrier into said slot to position said dog and permit longitudinal rocking movement thereof, and means extending on both sides of said cover for rotating said cam plate whereby said dog may be moved longitudinally and rocked in said slot.

3. In a closure mechanism having a cam-actuated dog slidably mounted within a slot in a dog carrier for longitudinal movement therein, a member projecting from the bottom of said dog carrier into said slot, and resilient means associated with said dog carrier for urging the outer portion of said dog downward about said member toward the bottom of said slot.

4. In a closure mechanism having a cam-actuated dog slidably mounted within a slot in a dog carrier for longitudinal and rocking movement therein, a member projecting into said slot from the bottom of said dog carrier and resilient means associated with said dog carrier and slidably engaging said dog for urging the outer portion of said dog downward about said member toward the bottom of said slot during said longitudinal movement of said dog.

5. In a closure mechanism having a cam-actuated dog slidably mounted within a slot in a dog carrier for longitudinal and rocking movement therein, a cam engaging an inner top portion of the dog, a fulcrum for the dog, resilient means associated with the dog carrier and slidably engaging the dog for exerting a turning moment around the fulcrum whereby the outer portion of

the dog is urged downwardly and the inner end of the dog is urged upwardly toward the cam during the longitudinal movement of the dog.

6. In a closure mechanism having a cam-actuated dog slidably mounted within a slot in a dog carrier for longitudinal and rocking movement therein, a cam engaging an inner top portion of said dog, an adjustable member projecting from the bottom of said dog carrier into said slot to position said dog and permit longitudinal rocking movement thereof, resilient means associated with said dog carrier and slidably engaging said dog for urging the outer portion of said dog downward against said member, and a second resilient means associated with said dog carrier and slidably engaging said dog for urging the inner portion of said dog upward toward said cam.

7. Closure mechanism comprising a rim, one or more dogs extending in a direction across the rim, a dog carrier for each dog comprising a slot guiding longitudinal movement thereof, a cam operable to actuate the dog longitudinally of itself in the slot alternatively to advance to or retract from a position opposite the rim, a fulcrum for the dog in the slot engaging the dog slidably during its longitudinal movement, resilient means operating between each carrier and its dog to urge the dog laterally of itself pivotally on the fulcrum in the direction away from the rim, and a cam operating to actuate the dog laterally of itself opposed to the resilient means into engagement with the rim.

8. Closure mechanism comprising a rim, one or more dogs extending in a direction across the rim, a dog carrier for each dog comprising a slot guiding longitudinal movement thereof, a cam operable to actuate the dog longitudinally of itself in the slot alternatively to advance to or retract from a position opposite the rim, a fulcrum for the dog in the slot engaging the dog slidably during its longitudinal movement, resilient means engaging the dog slidably during its longitudinal movement, and operating between each carrier and its dog to urge the dog laterally of itself pivotally on the fulcrum in the direction away from the rim, and a cam operating to actuate the dog laterally of itself opposed to the resilient means into engagement with the rim.
